UNITED STATES PATENT OFFICE.

FRANK DOMINELLI, OF OLEAN, NEW YORK.

WRENCH.

Application filed May 20, 1926. Serial No. 110,456.

This invention relates to wrenches of the sliding jaw type and aims to provide a means for facilitating the rapid adjustment of the sliding jaw as well as simple and efficient 5 means for maintaining the sliding jaw in predetermined adjusted position.

Another object will become apparent as the nature of the invention is better understood, the same comprising the novel form, combination, and arrangement of parts herein-after more fully described, shown in the accompanying drawing and claimed.

In the drawing wherein like reference characters indicate corresponding parts 15 throughout the several views:

Figure 1 is a side elevation of my improved wrench.

Figure 2 is a fragmentary vertical section taken substantially upon the line 2—2 20 of Figure 1.

Figure 3 is a perspective view of one of the locking members for maintaining the sliding jaw in adjusted position, and

Figure 4 is a perspective view of the retaining means for said member.

Now having particular reference to the drawing, my novel wrench constitutes the provision of a conventionally designed stationary jaw 5 formed upon or attached to 30 one end of a flat like handle 6 of predetermined length, one side of which is formed with transversely extending spaced beveled teeth 7.

Slidably arranged upon the handle 6 is 35 a sleeve 8 the inner end of which is formed with a jaw 9 complementary to the stationary jaw 5. Adjacent opposite ends of the sleeve 8 one side of the same is formed with sockets 10—10 that communicate at their 40 inner ends with the bore of the sleeve, the outer ends thereof being provided with annular flanges as at 11—11. Slidably arranged within the sockets are pins 12—12 the inner ends of which are formed with 45 beveled heads 13, the edges of which are adapted for engagement between the teeth 7 of the handle 6, for locking the sleeve against sliding movement upon said handle. Surrounding these pins between the head 13 50 and the flanges 11 of the sockets are expandable coil springs 14 that serve to normally maintain the heads in engagement beneath said teeth.

The outer ends of the pins project through 55 the flanges 11 of the sockets and have attached thereto metallic strips 15 that ex-

tend toward each other as clearly disclosed in Figures 1 and 2. The free ends of these strips are curved slightly outwardly and are formed with thumb or finger engaging enlargements 16. By reason of the free ends of these plates being bent outwardly, the same may be rocked upon the surface of the sleeve 8 for causing the pins to slide outwardly against the action of the spring 14 which will release the same from the teeth 7 of the handle 6 so as to permit the sliding of the sleeve upon said handle.

It will thus be seen that I have provided a highly novel, simple and efficient form 70 of wrench that is well adapted for all the purposes heretofore designated and even though I have herein shown and described the same as consisting of certain detail structural elements it is nevertheless to be 75 understood that departures may be had therefrom without effecting the spirit and scope of the appended claim.

Having thus described the invention, what I claim as new and desire to secure by 80 Letters Patents is:—

In a wrench of the class described, a handle, a stationary jaw formed on one end thereof, there being transversely extending spaced teeth formed on one side of the 85 handle, a jaw carrying sleeve slidably mounted on the handle, said sleeve having transversely arranged sockets formed in one side thereof adjacent its upper and lower ends, said sockets communicating at their 90 inner ends with the bore of the sleeve, an annular flange in the outer end portion of each socket, a pin arranged in each socket, a bevelled head on the inner end of each pin, a coil spring encircling each pin and disposed between the bevelled head on the inner end of the pin and the annular flange in the respective socket for normally holding the bevelled heads of the pins in engagement with the teeth of the handle, means 95 upon the outside of the sleeve for moving the pins out of engagement with the teeth, said means comprising a pair of metallic strips secured at their outer ends to the 100 respective pins, the outer end portions of the strips engaging the respective annular flanges in the sockets, said strips being bent outwardly at their inner ends in order that the same may be rocked upon the sleeve.

In testimony whereof I affix my signature.

FRANK DOMINELLI.
